DESIGN FOR A MIXER JAR

Heber L. Newell, Beacon, N. Y., assignor to The
Winsted Hardware Manufacturing Co., Win-
sted, Conn.

Application June 3, 1947, Serial No. 139,429

Term of patent 14 years

(Cl. D44—1)

To all whom it may concern:

Be it known that I, Heber L. Newell, a citizen of the United States and a resident of Beacon, county of Dutchess, and State of New York, have invented a new, original, and ornamental Design for a Mixer Jar, of which the following is a specification, reference being had to the accompanying drawing, forming a part thereof.

Fig. 1 is a top plan view of a mixer jar showing my new design; and

Fig. 2 is a side elevational view thereof.

I claim:

The ornamental design for a mixer jar, substantially as shown.

HEBER L. NEWELL.
